Specification of Letters Patent. Patented Nov. 17, 1914.

Application filed February 7, 1914. Serial No. 817,297.

To all whom it may concern:

Be it known that I, MARTIN A. DENINE, a citizen of the United States, residing at Spokane, in the county of Spokane and State of Washington, have invented certain new and useful Improvements in Aeroplanes; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in aeroplanes, the object in view being to provide a device which will be inherently balanced both forward, aft, and laterally, the invention contemplating aircrafts either of the monoplane or biplane type, and comprises various details of construction and combinations and arrangements of parts which will be hereinafter fully described, shown in the accompanying drawings and then specifically defined in the appended claims.

My invention is illustrated in the accompanying drawings, in which:

Figure 1 is a top plan view of an aeroplane made in accordance with my invention. Fig. 2 is an enlarged detail view of the under surface of one of the wings of the aeroplane. Fig. 3 is an end view of one of the wings, and Figs. 4, 5 and 6 are views taken on lines 4, 5 and 6 of Fig. 2.

Reference now being had to the details of the drawings by letter, A designates the body of the aeroplane which is made preferably of the shape illustrated with bluntly tapering forward end where the propeller C is mounted upon a shaft C' adapted to be driven by suitable motor power. The opposite, more acutely tapering rear end is provided with a lateral steering rudder N and the horizontally disposed tail piece O having control flaps D, D' which are adapted to be connected by the controlling wires D' which extend to a location adjacent to the operator of the craft.

B, B' designate wings, suitably braced and reinforced by means of the wires B' which are fastened to the ribs of the wings and also to said body portion of the craft. Said wings terminate in flexible tips or ailerons

E adapted to be connected by wires E' to a warping lever upon the body portion of the apparatus and adapted to be controlled by hand, allowing the tips each to warp in one direction. These tips are placed at a nonlifting angle or at a negative angle of from 1° to 2°. Said wings are made preferably of the particular shape and curvature shown in order that the surfaces may have the greatest amount of lateral, and fore and aft stability with a minimum amount of drift and loss of lift.

Upon reference to Fig. 1 of the drawings, it will be noted that the wings from their point of connection to the body portion at F are disposed at an inclination thereto, being slightly canted forward to the point G for substantially 1/3 the spread of the wings from the body, the cant forward being anywhere from 6 inches to 2 feet according to the spread of the wings. In the apparatus illustrated, the cant forward is substantially 1 foot and from the points G to H the main surfaces cant backward toward the tail, the cant backward being from 9 inches to 3 feet according to the spread of the wings, in the present craft the cant being substantially 1 foot, 6 inches. From the point H to the extreme tip of the wing the main surfaces cant back toward the tail and the tapering edge is preferably round off, making that part of the wing cant back at a greater angle than the surface from G to H.

In the main surfaces or wing, the camber or curve of the ribs is increased from the point G to the body and decreased from the point G to the tips of the wings. In the machine illustrated the increase of curvature is .5 inches per foot and the decrease is .35 inches per foot.

In an aeroplane, the main surfaces or wings of which extend on a straight line from body to tip or from tip to tip of wing, the center of pressure advances toward the front or entering edge of the wing as the angle of the wing is increased during flight and the center of pressure recedes as the angle of the wing is decreased during flight. In both instances the stability of the aeroplane fore and aft is destroyed for the aeroplane being balanced over the center of pressure has a tendency to further increase its angle of flight as the center of pressure moves forward, and the aeroplane stalls, decreases speed and either slides backward on

its tail or makes a sudden dive forward, for on losing speed the lift is reduced and the aeroplane drops toward the earth. In flight the aeroplane being balanced over the center 5 of pressure, as the angle of pressure advances and the center of weight remains constant, the forward advance of the center of pressure pushes up on that part of the wing, and the center of weight then being back of the 10 center of pressure pulls down that part of the wing and the angle of the wing being then above normal the machine loses speed and lift and drops. On a decrease of the angle of the wing during flight the opposite 15 effect is the result and the machine dives.

In the design of wing of my aeroplane, as the angle of the wing is increased during flight, the center of pressure retreats and the center of weight then being forward of the 20 center of pressure the aeroplane returns to its normal angle of flight. As the angle of the wing is decreased in flight, the center of pressure advances and the center of weight then being back of the center of pressure 25 the aeroplane returns to its normal angle of flight.

If the aeroplane for any reason increases its angle of incidence during flight, the surface from G to F is presented at a higher 30 angle to the air entering that surface. The pressure near the body is increased on account of the deep camber there being presented at a higher angle than during normal flight, and a deep camber lifts more at a 35 high angle of incidence than at a low angle if the same speed be maintained. At the same time the air entering at the point G is sliding toward the point F and compressing the air into the deep camber at F, thereby 40 making a high pressure point at F and that high pressure point being back of the center of weight (near the point X) or the line over which the aeroplane is balanced fore and aft makes the aeroplane return to its 45 normal angle of flight. At the same time the surface from G to the tip of the wing is presented at a higher angle of incidence to the breeze. The part of the wing near the tip has a very low camber, and a low or 50 negative angle of incidence, and in normal flight is lifting very little weight. When an increase of angle occurs the tip of the wing is presented at a lifting angle to the breeze and that part of the wing being back of the 55 point X and receiving a lifting pressure where there was little or none before, pushes up on that part of the wing, and returns the surface to its original position or normal angle of flight. Now I claim that the working 60 of these two parts of the wing in conjunction with each other is an improvement over either a wing extending on a straight line from body to tip or being only canted back toward the tail from the body to the 65 tip, for in an aeroplane whose wings are on

a straight line from the body to near the tip, the center of pressure advances as a larger angle of incidence is presented to the breeze during flight, and the center of pressure recedes as a lower angle of incidence is presented to the breeze, thereby destroying all inherent fore and aft balance. In an aeroplane whose wings only cant back toward the tail from the body to the tip, the center of pressure slowly recedes as a larger angle 70 is presented to the breeze and advances slowly as a lower angle is presented to the breeze during flight and consequently the righting effect is slow, but not only that a very large degree of head resistance is set 75 up on account of the air passing along the wing from the body backward and to the tip, and on account of it having to pass over so large an amount of surface a large amount of drag is created, and an expressive high 80 power plant has to be installed to get up enough speed to stay in the air. On my invention the air leaves the wing on a more direct line toward the rear edge and consequently does not set up such a large amount 85 of drag, and on account of the air reacting separately on two parts of the wing instead of only one a quicker return to the normal angle of flight is assured and consequently less drag is created. 90

The camber of the wing is increased from the point G to the point F at the body. The wing is attached to the body so that the highest part of the camber is on a line with the widest part of the streamline 100 body where it begins to taper toward the tail K. The air entering the wing between the points from G to F flows toward the rear edge of the wing and toward the body. The part of the wing at the body is attached to the body so that there can be no escape of air between the wing and the body. Now then the air flowing rearward and toward the body compresses the air entering nearer the point F into the highest 105 part of the camber near the body. The air on entering the wing between the points G to F seeks its easiest way of escape from the wing and that way is toward the highest camber of the wing at K. The 110 air entering between the points G and F and compressing itself into the highest part of the camber at the body creates a high pressure point there and the maximum 115 amount of lift per square foot of surface. So far the surface between G and F has only created a large amount of lift per square foot of surface. Now then, the air at high compression seeks its easiest mode of exit from the wing, and that place of 120 exit is rearward and against the part of the body where it tapers toward the rear; and in taking that mode of exit it presses against the tapering part of the body and on account of that pressure reacting against 125 130

the body pushes it forward in the same manner as an apple seed with its tapering end toward the palm of the hand, when pressed between the fingers, suddenly flies 5 forward. Therefore, I claim that an increase of camber from the point G to F helps the forward propulsion and increases the lift on that part of the wing and that less power is needed than on an aeroplane 10 whose wings are on a straight line from the body to the tip or only cant backward from the body to the tip, although either one may have an increase of camber toward the body. In an aeroplane, the wings of 15 which are on a straight line from body to tip and which has an increase of camber toward the body, the only result obtained is a slight increase of speed on account of less head resistance, and a reduction of 20 breaking stresses of the wing on account of there being less lift on the wing as the tip of wing is approached, than there is near the body. The air flows rearward and toward the tip of the wing and not rearward and 25 toward the body, therefore getting no compression and consequently less lift for the amount of surface used. In an aeroplane, the wings of which cant backward from the body to the tip, the slipping of the air 30 from the body to the tip is greater and consequently less lift is obtained for a given amount of surface and the only result obtained is a greater amount of inherent stability both fore and aft and lateral. 35 An aeroplane having wings extending on a straight line laterally from the body to the tip has very little or no inherent lateral stability but an aeroplane, the wings of which cant backward toward the tail, has 40 a small or large amount of inherent stability according to the degree of cant given them up to a certain degree when they become practically useless as lifting members. The farther the wing is canted back toward 45 the tail the higher is its amount of inherent stability, but the farther they are canted back the less lift they have and a higher degree of drag is created, making an installation of higher power necessary and, 50 on account of the extra weight added, is a detriment to the machine. In an aeroplane, the wings of which slant back toward the tail, inherent stability is obtained in the following way:-The air entering the wing 55 changes its direction from a direct line toward the rear to a line toward the rear edge of the tip. The air following the air which has already entered the wing changes its direction before entering the wing and 60 the consequent direction is toward the tip of the wing. Therefore, a stream of air is flowing from a point near the body to the tip. A sudden gust of air approaching the wing has to break down this stream of air 65 before it can strike the wing, and in doing so loses part of its force and also its direction and is turned toward the tip of the wing. When it does strike the wing, its direction is toward the tip and it spreads itself from the point at which it strikes 70 toward the tip. The gust of air has lost a part of its force in breaking down the stream of air flowing toward the tip and through changing its direction and the effect on that wing is partially lost. Now there is another action on 75 the wing besides the one just mentioned. This sudden gust of air on striking the wing sets up a higher amount of resistance on that wing and the wing is drifted slightly 80 backward, thereby canting the wing back so that the entering edge is presented at a larger degree of slant to the air than it was originally, and the result is loss of lift and a restoring of the aeroplane to its original 85 position laterally, for an aeroplane surface lifts the most when its entering edge is square to the breeze (according to past experiments). The action of the above mentioned aeroplane is slow and its speed is low 90 on account of the drag of such a shaped wing and an extra heavy gust of wind is liable to destroy its balance and the machine would be destroyed if some method of hand balancing was not employed. In my invention, I claim to have obtained a higher degree of inherent lateral balance by the following method: The wing is canted forward from F to G and then backward from G to 95 the tip of the wing. The air entering the 100 wing flows in two directions, from F to G toward the rear and toward the body and from G to the tip of the wing toward the rear and toward the tip. A stream of air is created near the front edge which flows 105 from G toward the body and from G toward the tip in just the same manner as in the aeroplane whose wings only cant back from the body to the tip, but the difference is that the air is flowing toward the body at one 110 part of the wing and toward the tip on the other part of the wing instead of only toward the tip as in the machine whose wings only cant back from the body to the tip. The front edge of each wing forms an open A 115 with the opening toward the rear on each side of the body and on account of the resistance they offer to the air entering them, act as two very narrow V-shaped rudders with their points toward the breeze. An 120 excess of pressure and consequent resistance on either wing will have a tendency to cause a retreat of the wing receiving that pressure and an advance of the wing on the opposite side. 125

A sudden gust of air approaching the wing on either side of the body partially changes its direction before striking the wing, because said gust of air is effected by the streams of air already banked up in 130

front of the wing. In striking the flow of air near the wing and changing its direction the gust of air loses part of its force, but at the same time slightly increases the speed 5 of the air nearer the wing. This increase of speed effects the aeroplane wing and on account of its increased resistance drifts said wing backward slightly so that by the time the gust of air hits the wing, the wing has 10 already begun to drift backward and it again loses part of its force. The gust of air then on striking the wing increases its lift and increases the speed of the wing toward the rear. The result is that part of the 15 wing from G to the tip is presented at a greater degree of slant to the breeze, as per dotted line M, and the resultant lift is less than at its normal angle. During the above operation, that part of the wing from F to 20 G is drifted back slightly and presents its entering edge at a straighter line to the breeze and the resistance of that part of the wing is increased and helps to drift the wing rearward. At the same time the com- 25 pression of air on that part of the wing is lessened and a loss of lift is the result for the wing from F to G lifts the most when it is presented at a slant forward for it then compresses the air entering thereon. At the 30 same time the wing on the opposite side is advanced and on account of a slight in- crease of speed gains a small amount of lift, at the same time it presents its entering edge from G to the tip of the wing at a straighter 35 line to the breeze and from F to G at greater cant forward. The pressure on the wing from G to the tip is increased on ac- count of it being presented at a better lifting 40 angle and the compression is also increased from F to G for the air entering near G flows on a more direct line from G to F into the high camber and against the streamline body. During this operation the aeroplane does not change its course of flight forward

to any appreciable extent for the resultant 45 pressures on each wing are nearly equal and the change from a high pressure on one wing to an equal pressure on the opposite wing is so rapid that the aeroplane cannot change its course over a few degrees. What- 50 ever change of course does occur can be im- mediately rectified by a warping of the flexible tips E, E which, being placed so far back of the center of the weight and pres- 55 sure of the whole wing, act merely as rudders to change the course of the machine.

By the provision of the flexible tips, when it is desired to turn the craft to the left, the warping wheel or lever may be turned to the left and which operation will cause 60 the tip on the left side to raise and receive a pressure on top which passes downward and backward. That side is immediately lowered and is drawn backward and the aeroplane banks and turns to the left. By 65 returning the tip to its normal position, the aeroplane straightens up and proceeds on its course.

What I claim to be new is:—

An aeroplane having a body portion pro- 70 vided with a tail piece, controlling flaps and rudder and having laterally spreading wings which are canted forward from the body a portion of the length of the spread of the wings, thence canted backward the balance 75 of the length of the spread of the wings, the camber increasing from the apex or forward portion of the wing toward the body at a greater degree per foot than the camber is decreased per foot from said apex 80 to the tip, as set forth.

In testimony whereof I hereunto affix my signature in presence of two witnesses.

MARTIN AIDAN DENINE.
